UNITED STATES PATENT OFFICE.

HENRY HOWARD, OF SEYMOUR, CONNECTICUT, ASSIGNOR TO TINGUE MANUFACTURING COMPANY, OF SEYMOUR, CONNECTICUT, A CORPORATION OF CONNECTICUT.

LOOM AND METHOD OF WEAVING DOUBLE-PILE FABRICS.

Application filed May 3, 1927. Serial No. 188,492.

This invention relates to pile weaving in which two fabrics are woven, at the same time, face to face, so as to produce two fabrics with uncut pile warp loops in the 5 face of each finished fabric, and more particularly to the weaving of fabrics, such as linen frize. The pile loops of such fabrics have usually been woven about cross wires, the wires being inserted at right angles to 10 the warp, and thereafter withdrawn. In accordance with the invention the use of cross wires is avoided and the weft threads of the fabrics when used to form a pile, are inserted above and below stationary, vertically rigid 15 ribbons, extending in the direction of the warp threads about which weft threads the pile loops are formed, the said pile weft being readily and easily withdrawn from the finished fabrics. The weaving is thus un- 20 interruptedly continued.

One of the objects of my invention is to provide vertically incompressible, stationary means above and below which and intermediate its ends the fabrics are woven, the 25 said means being adapted to separate the fabrics, one from the other, and being also adapted to form the base of the sheds when the pile warp threads are weaving the pile loops and to serve as a stop and support for 30 the pile weft threads passed thru the said sheds, the height of the said means thereby determining the height of the pile loops of the respective fabrics.

Another object of the invention is to provide means including two shuttles whereby the pile loops of the fabrics whose ground wefts are inserted by one shuttle, receive a pile weft thread from the other shuttle. The pile loops of each fabric issue disconnected 40 from each other. The pile wefts are also unconnected across the fabric to the ground wefts of the same fabric, the only connection, being at the selvages of the fabrics. This connection between the pile weft threads of one 45 fabric and the ground weft threads of the other fabric at the selvages, is severed before the fabrics are delivered by the loom. This provides a loose pick filling weft for the pile loops.

Another object of the invention is to provide means, whereby the selvage connections of the loose pick pile wefts of one fabric and the ground wefts of the opposing fabric are formed in a loop transverse to the plane of 55 the weft threads, together with means for

severing the loops so formed, thus parting the two cloths and permitting the loose pick pile wefts to be readily and easily withdrawn as by hand from the pile loops of the fabrics.

With the above and other objects in view, 60 my invention consists in the parts, improvements and combinations more fully pointed out hereinafter.

Turning now to the drawings which illustrate one embodiment of the invention and 65 show sufficient parts of a loom to illustrate the invention:

Figure 1, is a diagrammatic view of the double fabric loom, when weaving the pile loops and pile weft thread for the upper fabric and the corresponding ground weft, the 70 left hand end of the figure being enlarged, the pile weft and corresponding ground weft for the upper fabric, about to be woven being shown in dotted circles.

Figure 2, is a diagrammatic view of the loom when performing the same operations for the lower fabric.

Figure 3, is an enlarged diagrammatic view of the fabrics, showing the cloth separating ribbons and the method of weaving the 80 fabrics.

Figure 4, is an enlarged detail view showing the position of the threads when weaving the pile loop and weft thread for the 85 lower fabric and the corresponding ground.

Figure 5, is a diagrammatic view showing the two series of pile loops without showing the ground of the fabrics.

Figure 6, is a top plan view showing the 90 distribution of the threads, the ribbons and the temple and cutter.

Figure 7, is a perspective view of the ribbons passing thru the notcher bar, which prevents the ribbons from twisting.

Figure 8, is a horizontal section showing the heddles and their threads.

Figure 9, is a diagrammatic view of the loom showing the binder threads.

Figure 10, is a perspective view showing 100 the formation of the transverse loops in the pile weft thread.

Figure 11, is a side elevation showing the transverse loops of the pile weft threads during the cutting operation.

Figure 12, is a perspective view of the finger and temple, showing the loops in the pile weft threads, sliding along the finger of the temple.

It will be understood that the invention 110

about to be described, may be applied to and carried out on any type of loom, and that any desired weave may be employed.

In the drawings, two pile fabrics are shown being woven face to face, at the same time. For convenience and simplicity, the drawings merely show two series of ground warp threads and one series of pile warp threads for each fabric. The number of pile or ground threads may be varied. The threads used in the weaving and the weaving sheds are designated by reference letters and reference numerals are applied to the various parts of the loom illustrated.

15 Suitable tensioning means and let-off beams (not shown) are provided for the respective warp threads. Ground warp threads A, B, for the top fabric are shown passing over guiding roller 1, and about guiding roller 2, 10 and linen pile warp threads C, for the upper cloth, are shown passing about guiding roller 3. Ground warp threads D, E, and linen pile warp thread F, for the lower fabric pass about guiding rollers 4, and 5, respectively, see Figures 1 and 2.

A series of heddles is provided for each series of ground warp threads and each series of pile warp threads, of the respective fabrics. In Figures 1 and 2, however, only one heddle 30 of the series is shown for one thread of the series. As illustrated in these figures, upper ground warp thread A, passes thru the eye 6 in heddle 7, upper ground warp thread B, passes thru eye 8 in heddle 9, lower ground 35 warp thread D, passes thru eye 10 in heddle 11 and lower ground thread E, thru eye 12, in heddle 13. Upper pile warp thread C, passes thru the eye 14, in heddle 15, and lower pile warp thread F, passes thru eye 16 in 40 heddle 17. In the same manner the respective threads pass thru the eyes of their heddles, across the cloth, as shown in Figure 8, where the same numbers are employed for corresponding parts, the arrow indicating the 45 direction of travel of the cloth.

Each series of heddles, carrying the threads, is provided with its separate harness frame (not shown) and is operated by suitable mechanism (not shown) such as cams, in accordance with the weave desired.

50 A reed 18, upon a swinging lay 19, is provided, the reed having dents 20. The warp threads pass from the eyes in the heddles, thru the dents 20 of the reed 18, and forward 55 toward the breast beam 21 of the loom.

Means are provided above and below and intermediate the ends of which the two fabrics are woven face to face. The said means 60 separate the fabrics from each other, and form the base of the sheds when the pile threads are weaving the pile loops of the two fabrics, and serve as a stop and support for the pile weft threads, passing thru said sheds. The height 65 of the said means which is greater than their width determines the height of the pile loops

of the respective cloths. These means also serve as a race for the upper shuttle when the pile weft for the pile loops of the lower fabric is being thrown.

As shown in the drawings, these means consist of a series of stationary, vertically incompressible, metallic ribbons 22. See figures 1 to 8. The ribbons 22 are so constructed that they will not give and will not compress during the weaving operations. Each ribbon 22, 75 is provided at one end with an eye 23, by which it is anchored to a transverse bar 24.

Means are provided to prevent twisting of the ribbons about their longitudinal axes. In the embodiment of the invention illustrated, 80 a cross bar 25, is provided at the front of the transverse bar 24, and near the heddles of the loom. The bar 25, is provided with a series of uniformly spaced notches 26, throughout its length. The ribbons 22, pass from their anchorage in the transverse bar 24, and respectively thru the notches 26, in the cross bar 25, forward between the heddles, and are of a thin width permitting them to pass freely thru the dents 20 in the reed 18 (see particularly Fig. 6). The ribbons 22, extend forward of the reed and their free ends 22a extend beyond the falls of the fabrics, so that the fabrics are woven above and below and intermediate the ends of the ribbons. 90

The notches 26, in the bar 25, are made of a size corresponding to the width and height of the ribbons 22, thus holding the ribbons stationary and unyielding so that they will not twist. The number of notches in bar 25, 100 corresponds to the number of dents 20, in reed 18, and the notches and dents are in registering relation, so that the ribbons may pass thru the dents, of the reeds (see Fig. 6) being thin enough to allow the reed to pass back and forth freely along them in its beating-up operation, without interference. The transverse bar 24 and the notches 26 in the cross bar 25, hold the ribbons from twisting and buckling the dents in the reed. 105

The ribbons thus extend lengthwise of and between the two fabrics and parallel to the path of travel of the fabrics thru the loom, thus separating one fabric from the other. 110

The height of the vertically incompressible, stationary ribbons 22, determines the height of the pile loops of the respective fabrics. 115

The ribbons 22, are suitably spaced, across the width of the cloth to permit the passage of the pile warp threads between them and above and below them in the weaving method, hereinafter described. It is only necessary to supply a sufficient number of ribbons to form a suitable race for the upper shuttle and a support for the pile weft threads thrown by the shuttle. 120

In the embodiment of the invention illustrated, one ribbon is provided for every other notch and passes thru alternative dents 20 of the reed 18 (see Figure 6). 130

When reeds having dents of different sizes and numbers are used, the notched bar and ribbons are correspondingly changed.

Means are provided for weaving the two fabrics face to face above and below and intermediate the ends of the ribbons.

As illustrated, (see Figs. 1 and 2) two shuttles are provided. One shuttle 27, operates above and the other shuttle 28, operates below, and both operate intermediate the ends of the ribbons. The lower shuttle 28, is adapted to pass a weft thread G, thru pile shed P, formed, as hereinafter described, below the ribbons 22 (see Figure 1), and the upper shuttle 27, is adapted to pass a weft thread H, thru pile shed P', suitably formed above the ribbons 22, see Figure 2. When a pile loop for the upper cloth, with an inserted pile weft, is to be woven, the heddles 15, carry pile warp threads C, thru the space between the ribbons 22, and below the ribbons (see Fig. 1), so that the pile threads C, and the ribbons 22, form a shed P, thru which the lower shuttle 28, passes weft thread 25 G. After the weft is thrown the pile warp threads C, are returned upward carrying the weft thread G, with them, until the weft thread reaches and is stopped by ribbons 22, forming the base of the shed thru which the 30 weft thread has been passed. The ribbons 22, thus determine the height of the pile loop of the upper cloth. When the pile loop for the lower cloth is formed, heddle 17 carries pile warp thread F, thru the spaces between the 35 ribbons 22, and above the ribbons, so that the pile warp thread F and the ribbons 22 form a pile shed P'. Thru this shed, the shuttle 27, passes a pile weft thread H. The ribbons 22 now provide a race for the upper 40 shuttle 27 and form a base for the pile shed P', also supporting the pile weft H in its position, (see Figs. 2 and 4), and so determine the height of the pile loop of the lower cloth. It will thus be seen that the height of the 45 ribbons 22, determines the height of the pile loops of the respective fabrics and that variations in the height of the pile loops may be made by providing another set of ribbons and suitably altering their height.

50 Means are provided for inserting a single loose pick filling weft in the pile loops of each fabric, so that the pile loops of both fabrics issue unconnected from each other across the face of the fabric so that the pile 55 wefts of one fabric are not connected to the ground of the same fabric.

As shown in the drawings, (Figs. 1 to 5) the weft thread G, carried by shuttle 28, is normally passed thru suitably formed 60 ground sheds so as to provide ground wefts for the ground of the lower fabric. When the pile loops for the upper fabric are to be formed, the ground threads, D, E, of the lower fabric are then moved out of the path 65 of travel of this weft thread G (see Fig. 1),

and the weft is now passed only thru the pile shed P. It thus becomes a pile weft for the upper cloth. After this it resumes its passage as a ground weft thru ground sheds of the lower fabric. In the same manner the 70 weft thread H, which is normally passed, by shuttle 27, thru ground sheds to form the ground wefts for the upper fabric is also passed to form a pile weft for the pile loops 75 of the lower fabric. When these pile loops for the lower fabric are to be formed, above the ribbons 22, the upper ground threads A, B, are then moved out of the path of weft thread H, so that the thread only passes thru the pile shed P' (see Fig. 2), so as to 80 form only a pile weft for the lower fabric, after which the weft thread H, resumes its passage thru the ground sheds, so as to form ground wefts for the upper fabric. In this way the pile wefts of both fabrics issue un- 85 connected from each other and are not connected to their respective grounds. The pile loops of one fabric thus receive a loose pick weft thread, held in place by the ribbons 22, between the fabrics, and are joined only to 90 the ground wefts of the other fabric.

It will be observed that one or more ground wefts can be inserted at the base of the pile loop, according to the plan of weaving desired, two ground wefts being shown so 95 woven in the base of the pile loop.

Means are provided whereby the connections between the ground wefts of each fabric and the pile wefts of the opposite fabric, are formed in the selvages of the fabrics in 100 loops transverse to the plane of weaving of the weft threads and means are also provided for severing the loops so formed, so that the loose pick filling wefts for the pile loops may thereafter be readily withdrawn. 105

Binder threads are provided for each fabric, at each selvage of the fabrics, the binder threads running in the direction of the warps (see Fig. 9). These binder threads preferably consist of pairs of binder threads L, for 110 each selvage of the upper fabric, and pairs of binder threads M for each selvage of the lower fabric. The selvages of the fabrics in which the binder threads operate, are not provided with pile warp threads.

As shown in the drawings (see Fig. 9) the binder threads are supplied from the rear of the loom under suitable tension from the let-off beams (not shown), the threads L of the upper fabric passing thru eye 29 in heddle 115 30, and the threads M, of the lower fabric passing thru eye 31, heddle 32 (see Figure 9). Heddle 30 carrying binder threads L, is mounted on the same harness frame that carries heddles 15, thru which pile warp 120 threads C for the upper fabric pass, and heddle 32, carrying binder threads M of the lower fabric, is mounted in and actuated by the same harness frame operating heddle 17, 125 thru the eye of which the pile warp thread 130

F of the lower fabric passes. By these means upper binder threads L are operated with and similarly to upper pile warp threads C, and lower binder threads M, are operated in the same manner as lower pile warp threads F.

When the pile warp threads C of the upper fabric are carried below the ribbons 22, to form pile shed P, the binder threads L, one on the inside and one on the outside of each selvage of the fabric are also carried down with the pile threads C. The shuttle 28, passing weft thread G, thru the pile shed P, Figure 1, also passes this weft thread above the binder thread L. After shuttle 28, has passed the weft thread G, thru the pile loops and above the binder threads, it thereafter continues passing the weft thread G, thru ground sheds as a ground weft for the lower fabric. When the pile threads C, are returned upward, above the ribbons, the binder threads L, are also carried upward by their similarly operating heddle. The binder threads engaging the weft thread G, carry it upward and then out of its normal plane of travel. The inner and outer binder threads L, thus serve to carry upward the portion of the weft G, extending over the width of the selvage when it is passed thru the pile loops for the upper fabric. At the edge of the selvage, the weft is allowed to drop and resume its function as a ground weft thread for the lower fabric. When the pile loops for the lower fabric are to be formed, pile warp threads F, are carried above the ribbons 22, and the binder threads M, are carried up with the pile warp threads. The upper shuttle 27, then passes weft thread H, thru the pile shed P', and beneath the binder threads M, in the selvages of the fabrics. The subsequent return of the pile warp threads F and the binder threads M, will carry weft thread H, downward with them, out of its normal path of travel. The binder threads thus operate to form a transverse loop of the weft threads in the selvage of the fabrics, from the point where they leave the pile loops of one fabric to the point where they enter the ground sheds of the other fabrics (see Figs. 10 to 12).

Means are provided for severing the transverse loops formed of the weft threads by the binder threads, so that the pile weft threads may be readily withdrawn.

As the fabrics are woven and beaten up, they advance thru the loom and pass off the free ends 22^a of the ribbons 22, to their respective take-up rollers 33, 34. The pile weft of one cloth being only connected to the ground wefts of the opposite fabric at the selvages of the fabric, the fabrics after leaving the ribbons 22, will separate across their faces, one from the other (see Figure 3).

As shown in the drawings (see Figs. 6 and 12) a right-angled temple 35, is provided at

each side of the loom. Each temple is provided with a horizontally projecting pointed finger 36. The projecting finger 36, is arranged in the path of the selvages of the fabrics. As the fabrics are advanced, the finger 36, enters the transverse loops formed in the pile weft threads, so that the loops pass around the fingers 36, and pass along them as the fabrics advance, (see Figs. 10 to 12). The outside joint of each right-angled temple 70 is sharpened, so that when the loops reach the joint, they will be severed. The ground weft threads for the fabrics lie in their respective horizontal planes (see Figs. 10 to 12) and consequently do not pass around the finger 36, the ground wefts for the upper fabric passing above the finger and the ground wefts for the lower fabric passing below the finger. Thus only the connection 75 between the ground weft and the pile weft is severed by the sharpened joint of the temple 35. The ground weft is left intact. The pile weft thread may then be easily withdrawn from the pile loops of the finished fabrics. 90

Coming now to the method of introducing ground warps and pile warps above and below the fabric separating ribbons so as to insert one or more ground wefts in the ground of fabric at the base of the pile loop and 95 to insert a loose weft in the top of the pile loop of the same fabric, it will be understood that any desired distribution of pile warp threads and ground warp threads may be employed and the ground wefts may be inserted as desired. As shown in the drawings, the ground warp threads A, B, of the upper fabric and the ground warp threads D, E of the lower fabric are suitably manipulated to form a succession of ground sheds 100 (see Figures 3 and 4), thru which shuttles 27 and 28, pass weft threads H and G, respectively.

After a plurality of ground wefts are passed thru ground sheds in each fabric 110 (three ground wefts being shown in the drawings), the upper ground threads A and B, are formed into a ground shed for the upper fabric, thru which shuttle 27 passes weft thread H. The pile warp threads C of the same upper fabric are carried between the spaces in ribbons 22, and below the ribbons, so as to form a pile shed of the pile warp threads C and the ribbons 22. The ground threads D, E, of the lower fabric are moved out of the path 120 of travel of lower weft thread G. The shuttle 28, passes weft thread G, thru the pile shed P, at the same time that shuttle 27 passes weft thread H, thru a ground shed for the same fabric (see Figure 1). The pile warp threads 125 C are then carried upward by the reciprocation of their heddles 15, and carry the weft thread G upward with the pile loops, until they reach and are stopped by ribbons 22. The ground threads D, E, of the lower fab- 130

ric are then formed in a ground shed thru which this weft thread G, is now passed by shuttle 28, and the pile warp threads F, of the lower fabric are carried between the spaces and above the ribbons 22, and the ground warp threads A, B, of the upper cloth are moved out of the path of travel of upper weft thread H. The pile warp threads F and the ribbons 22, now form a pile shed P', thru which the upper shuttle 27, passes weft thread H, at the same time shuttle 28, is passing weft thread G, thru a ground shed formed of the ground threads of the same fabric (see Figure 2). The shuttle 27, when passing thru the pile shed P' see Fig. 4, travels along a race now formed by the ribbons 22. After this the heddles carrying the thread F, are returned downward, the pile threads forming a loop for the lower fabric, about the weft thread H. The weft thread H, is supported upon and by the ribbons 22. The pile loops for each cloth having thus been formed each with an inserted loose pile weft, the weaving of the grounds of both fabrics is continued.

25 When the pile weft is passed thru the respective pile loops, the coacting binder threads in the selvages operate as above described to form a loop of the weft threads transverse to their normal plane, between the point where 30 the pile weft leaves the pile shed of one fabric and where it passes thru the ground shed of the other fabric.

As the weaving proceeds the fabrics are beaten up in the usual manner and advanced thru the loom. Before the fabrics reach the free ends of ribbons 22, on their way to their respective take-up rolls, the transverse loops of the weft threads pass upon the fingers of the temples at each selvage. As the fabrics pass further forward the transverse loops sliding along the fingers are severed as they reach the right-angled joint in the temples, as above described, thus completing the separation of the fabrics and allowing the pile weft thread to be readily withdrawn, as by hand.

It will be understood that one embodiment of the invention has been shown and described and that changes may be made in the loom and method without departing from the principles of the invention.

Claims:

1. A loom for weaving double pile fabrics, face to face, at the same time, including in combination, vertically incompressible fabric separating and pile weft supporting ribbons, of greater height than width, the height of said ribbons determining the height of the pile of both fabrics, said ribbons extending lengthwise of the loom and between the two fabrics, means for supplying ground warp, pile warp and weft threads for each fabric, and means for weaving said fabrics above and below and intermediate the ends of the said ribbons.

2. A loom for weaving double pile fabrics, face to face, at the same time, including in combination, vertically incompressible fabric separating and pile weft supporting ribbons, of greater height than width, the height of 70 said ribbons determining the height of the pile of both fabrics, the said ribbons extending between and parallel to the path of travel of the fabrics, means for supplying ground warp and pile warp threads for each fabric, 75 means for forming sheds consisting of the pile threads of each fabric and the ribbons, and means for passing a pile weft thread thru the sheds so formed.

3. A loom for weaving double pile fabrics 80 face to face, at the same time, including in combination, vertically incompressible stationary, fabric separating and pile weft supporting ribbons, of greater height than width, the height of said ribbons determining the 85 height of the pile of both fabrics, means for supplying ground warp and pile warp threads to each fabric, a shuttle adapted to pass a weft thread above and intermediate the ends of said ribbons, another shuttle adapted to 90 pass a weft thread below and intermediate the ends of said ribbons, means for forming a shed of the ground threads of one fabric, means for forming, a second shed of the pile warp threads of the same fabric and ribbons 95 and means for simultaneously passing one shuttle thru the former shed and the other shuttle thru the latter shed, so as to simultaneously provide a weft thread for the ground and a weft thread for the pile loops 100 of the same fabric.

4. A loom for weaving double pile fabrics face to face at the same time, including a plurality of spaced, vertically incompressible, metallic ribbons, extending lengthwise of the 105 loom and between the fabrics, means for supplying ground warp and pile warp threads for each fabric, an upper shuttle and a lower shuttle, means for passing the pile warp threads of the upper fabric below said ribbons, to form a shed with the ribbons thru which the lower shuttle is adapted to pass a pile weft thread, and means for raising the pile warp threads of the lower fabric above said ribbon to form a shed with the ribbons, 110 thru which the upper shuttle is adapted to pass a pile weft thread, the ribbons forming a stop for the pile weft thread of the upper fabric and a support for the pile weft thread 115 of the lower fabric, the height of the ribbons determining the height of the pile loops of the respective fabric.

5. A loom for weaving double pile fabrics including in combination a plurality of vertically incompressible spaced ribbons, whose height determines the height of the pile of both fabrics, a transverse bar for the ribbons in the rear of the loom, means for anchoring said ribbons to said bar, the ribbons extending lengthwise of the loom, between the fab- 120 125 130

rics parallel to their path of travel, and having free ends, means for supplying ground warp, pile warp and weft thread to said fabrics and a pair of shuttles throwing the wefts of the fabrics above and below and intermediate the ends of said ribbons.

6. A loom for weaving double pile fabrics including in combination, a notched crossbar extending transverse of the loom, a transverse bar, a plurality of metallic ribbons secured to said transverse bar and lengthwise of the loom and passing thru the notches in said crossbar, the notches being of the same width as the ribbons, thereby holding the ribbons vertically rigid and stationary, the said ribbons extending between the fabrics, means for supplying ground warp, pile warp and weft threads for the fabrics and means for weaving the fabrics, above and below and intermediate the ends of said ribbons.

7. A loom for weaving double pile fabrics, including a reed, provided with dents in combination with a plurality of ribbons, whose height determines the height of the pile of both fabrics, a notched cross-bar mounted in the rear of the loom, the number of notches in said cross-bar being equal to the number of dents in said reed and arranged in registering relation thereto, the said ribbons passing thru the notched crossbar and thru dents in the reed and having free ends extending between the fabrics, means for supplying ground warp, pile warp and weft threads for the fabrics and means for weaving the fabrics above and below and intermediate the ends of the ribbons.

8. A loom for weaving double pile fabrics, including in combination, a plurality of vertically incompressible ribbons, whose height determines the height of the pile of both fabrics, said ribbons extending lengthwise of the loom and having free ends between the fabrics, means for supplying ground warp and pile warp threads and means for supplying ground weft and pile weft threads for the fabrics, means for weaving the fabrics above and below and intermediate the ends of said ribbons, means for forming loops in the pile weft threads transverse to the plane of said weft threads and means for severing the said weft loops.

9. A loom for weaving double pile fabrics, including in combination, a plurality of vertically incompressible ribbons, extending lengthwise of the loom between the fabrics, means for supplying ground warp and pile warp threads, means for supplying ground weft and pile weft threads, for the fabrics, means for weaving the fabrics, above and below and intermediate the ends of said ribbons, means for forming loops in the weft threads between the pile of each fabric and the ground of the opposite fabric transverse to the plane of said weft threads, said means comprising a pair of binder warp threads ar-

ranged in each selvage of each fabric, and means for severing the loops so formed.

10. A loom for weaving double pile fabrics, including in combination, a plurality of vertically incompressible ribbons, extending lengthwise of the loom between the fabrics, means for supplying ground warp and pile warp threads and means for supplying ground weft and pile weft threads for the fabrics, means for weaving the fabrics above and below and intermediate the ends of said ribbons, a plurality of binder warp threads for each fabric, said binder threads being raised and lowered in unison with the pile warp threads of their respective fabrics, so as to form loops in the weft threads between the pile of each fabric and the ground of the opposite fabric, transverse to the plane of the weft threads, and means for severing the loops so formed.

11. A loom for weaving double pile fabrics, including in combination, a plurality of vertically incompressible ribbons, extending lengthwise of the loom between the fabrics, means for supplying ground warp and pile warp threads, and means for supplying ground weft and pile weft threads for the fabrics, means for weaving the fabrics above and below and intermediate the ends of the ribbons, a plurality of binder warp threads for each fabric, said binder threads forming loops in said weft threads between the pile of each fabric and the ground of the opposite fabric transverse to the plane of the weft threads, and means forward of the loom, the said means adapted to enter the loops in the weft threads and hold them distended, and means for cutting the said loops.

12. A loom for weaving double pile fabrics, including in combination, a plurality of vertically incompressible ribbons, extending lengthwise of the loom between the fabrics, means for supplying ground warp and pile warp threads and means for supplying ground weft and pile weft threads for the fabrics, means for weaving the fabrics above and below and intermediate the ends of said ribbons, a plurality of binder warp threads for said fabrics, the binder threads being adapted to form loops in the weft threads between the pile of each fabric and the ground of the opposite fabric transverse to the plane of the weft threads, a pair of temples secured to each side of the loom near the ends of the said ribbons, said temples each having a projecting finger adapted to enter the loops formed in the pile weft threads, and means for severing the said loops.

13. A loom for weaving double pile fabrics, including in combination, a plurality of vertically incompressible ribbons extending lengthwise of the loom between the fabrics and having free ends, means for supplying ground warp and pile warp threads and means for supplying ground weft and pile weft threads and

weft threads for each fabric, means for weaving the fabrics above and below and intermediate the end of said ribbons, a plurality of binder warp threads for each fabric adapted to form loops in the weft threads between the pile of each fabric and the ground of the opposite fabric transverse to the plane of the weft threads, a pair of take-up rollers, one for each finished fabric, and a pair of right-angled temples, each with a projecting finger adapted to enter the pile weft loops, said temples and fingers being arranged near the free ends of the ribbons.

14. The method of pile weaving two fabrics, face to face, one above the other, at the same time, above and below a vertically incompressible fabric separating and pile weft supporting means, and intermediate its ends each of said fabrics having ground warp threads and pile warp threads, which consists in weaving one of said fabrics by forming a shed of the two series of ground warp threads of one fabric, passing a ground weft thru said shed, at the same time forming another shed of the pile warp threads only of the same fabric and the vertically incompressible weft supporting means, and passing a weft for the said pile warp threads, within said latter shed, so formed thus forming pile loops in said fabric each with an inserted weft.

15. The method of pile weaving two fabrics one above the other, face to face, at the same time, above and below an unyielding fabric separating and the pile weft supporting means, each of said fabrics having ground warp threads and pile warp threads, which consists in forming a shed of the two series of ground warp threads of the first fabric, passing a first thread thru said shed so as to form a ground weft, at the same time, forming a second shed of the pile warp threads of the first fabric and the unyielding weft supporting means, passing a second thread thru said second shed thus forming a pile weft for said pile warp threads, then forming a third shed of the two series of ground warp threads of the said fabric, passing said second thread thru said third shed so as to form a ground weft for said second fabric, and simultaneously forming a fourth shed of the pile warp threads of the second fabric and the weft supporting means, and passing the first thread thru said fourth shed.

16. The method of pile weaving two fabrics one above the other, face to face, at the same time, above and below vertically incompressible fabric separating and pile weft supporting means, each of said fabrics having ground warp threads and pile warp threads, which consists in forming a shed of the two series of ground warp threads of the first fabric, passing a first thread thru said shed, so as to form a ground weft, at the same time forming a second shed of the pile warp

threads of the first fabric and the fabric separating and weft supporting means, passing a second thread thru said second shed thus forming a pile weft for said pile warp threads, then forming a third shed of the two series of ground warp threads of the second fabric, passing said second thread thru said third shed, so as to form a ground weft for the second fabric, thereby connecting the pile weft of first fabric with the ground weft of the second fabric, simultaneously forming a fourth shed of the pile warp threads of the second fabric and the weft supporting means, and passing the first thread thru said fourth shed, so as to form a filling weft for the said pile warp threads of the second fabric, and also connecting the pile weft thread of the second fabric with the ground weft of the first fabric, and thereafter severing this connection.

17. The method of pile weaving two fabrics, one above the other, face to face, at the same time, above and below vertically incompressible fabric separating and pile weft supporting means, each of said fabrics having ground warp and pile warp threads, which consists in forming a first shed of the two series of ground warp threads of the first fabric, passing a first thread thru said shed, so as to form a ground weft, at the same time forming a second shed of the pile warp threads of the first fabric and the fabric separating and weft supporting means, passing a second thread thru said second shed, so as to provide a single pile weft for the pile warp threads, then forming a third shed of the two series of ground warp threads of the second fabric, passing said second thread thru said third shed, so as to form a ground weft for said second fabric and thereby connecting the pile weft thread of the first fabric to the ground weft of the second fabric, and simultaneously forming a fourth shed of the pile warp threads of the second fabric and the weft supporting means, and passing the first thread thru said fourth shed so as to form a single weft for the pile warp threads of the second fabric, and also connecting the pile weft of the second fabric to the ground weft of the first fabric and thereafter cutting the connections so formed and withdrawing the loose pile wefts from the pile loops of each fabric.

18. Steps in the method of pile weaving two fabrics face to face, at the same time, above and below fabric separating and pile weft supporting ribbons, above which a weft thread is adapted to be passed and below which another weft thread is passed, which consists in forming a ground shed between the ground warp threads of one fabric, passing one of said weft threads thru said shed simultaneously forming a pile shed between the pile warp threads of the same fabric and the weft supporting ribbons passing the other weft thru said pile shed only, thus inserting a

pile weft, moving the ground warp threads of the second fabric out of the path of traverse of the latter pile weft thread, so that the pile weft thread will not then be woven into the ground of the second fabric.

19. The method of pile weaving two fabrics, face to face at the same time, above and below unyielding fabric separating and pile weft supporting ribbons, which consists in forming series of ground sheds of the ground warp threads of each cloth, intermittently forming pile sheds with the pile warp threads of each fabric passing each of two weft

threads respectively thru the ground shed of one fabric and the pile sheds of the other fabric, and weaving binder threads in the selvages of each fabric, operating the binder threads of each fabric so that they form transverse loops in the weft threads between the ground of one fabric and the pile of the second fabric, and thereafter cutting the loops so formed.

In testimony whereof, I have signed my name to this specification.

HENRY HOWARD.
